CONTROL APPARATUS FOR SHEET FEEDING DEVICES

Daniel Broido, Cockfosters, near Barnet, England

Application May 18, 1942, Serial No. 443,541
In Great Britain August 15, 1941

10 Claims. (Cl. 209—111)

This invention relates to machines through which paper and like sheets are passed, such machines being provided with feeding devices for feeding the paper or like sheets into the machine.

It has been found that however carefully the feeding device is adjusted sheets will occasionally be fed into the machine in inaccurate alignment with parts of the machine which are to act on, or co-operate with, the sheets.

Further, in some machines of the kind in question, for example the assorting machine disclosed in my prior U. S. A. Patent No. 2,319,108, printed sheets are to be fed into the machine; in such cases in order to be acted upon properly by the machine, not only must the sheets be fed accurately into the machine, but the printed matter must also be accurately positioned on the sheet in order to obtain correct operation of the machine. Again, it is possible for the feeding device to pick up and forward to the machine more than one sheet.

Further the machine may miss a sheet, or a blank sheet may be fed through the machine.

All these possible inaccuracies may lead to faulty operation of the machine, particularly where, as in the apparatus disclosed in the above mentioned prior specification, the machine includes a photo-electric analysing device for analysing marks on the sheets passing through the machine.

Sheets which have been incorrectly printed or fed in any one of the ways above described are referred to in the appended claims as "incorrect" sheets, in contradistinction to other sheets termed in the appended claims "correct" sheets.

The object of the invention is to provide means for ensuring that the operation of the machine is effected only by correct sheets.

The accompanying drawings illustrate, by way of example, one embodiment of the present invention incorporated in the assorting machine described in my aforesaid prior Patent No. 2,319,108.

In the drawings:

Figures 1 and 1a together represent a vertical longitudinal section through a machine fitted with a control device according to the invention;

Figure 2 is a vertical transverse section on line I—I of Figure 1;

Figure 3 is a plan view taken substantially on line III—III of Figure 1;

Figure 4 is a partial side view of the machine;

Figure 5 shows a record intended for use with the control device according to the invention;

Figure 6 is a side view, similar to Figure 4, of a modified control device according to the invention;

Figure 7 is a partial section on line VII—VII of Figure 6; and

Figures 8 and 9 illustrate variations of control marks for use with the control device according to the invention.

For a full description of the construction and operation of the assorting machine reference is made to my prior patent above referred to. Figures 1, 2, 3 and 4 of the present application correspond to Figures 1, 2, 3 and 8 respectively, of said prior patent. The machine is adapted to assort or segregate records, such as shown in Figure 5, which have certain information recorded by selectively blacking in the index areas 98 provided for this purpose, each index area having a particular significance.

The operation of the machine is, briefly, as follows: The records 13 are stacked in a paper container 6 (Figure 1), and are fed between a drum 21 containing a photocell 80, and a lamp 72. The feeding device is of a known kind in which the top sheet 13 is first separated by buckling it between the feed roller 14 and a stop bar 15 (or the back plate 8), thereby withdrawing it from underneath spring-loaded fingers 16, whereupon the feed roller 14 reverses its movement and causes the paper sheet to pass over the top of the fingers 16 and between guides 17, 18 on to stops 19 carried on paper aligning fingers 20 pivotally mounted in a flap of the drum 21. The means for operating the feed roller 14, as also the means for operating the pinions 10 to raise the paper container 6, are not shown in the drawings but are fully described in U. S. A. Patent specification No. 2,165,231. Drum 21 has a number of apertures 91 corresponding in number and arrangement to the index-points 98 which are normally closed by plugs 92. In order to segregate records having certain index-points blackened, the apertures 91 in the drum corresponding to these index-points are opened. During each rotation of drum 21, these open apertures, if the record is fed correctly through the machine, are aligned with the corresponding index-points, and if all these index-points contain black marks, no appreciable amount of light will penetrate to the photocell 80, and the record will be guided underneath a sorting flap 69 into a bin 70 reserved for

“accepted” records. However, if a record is not

marked in the required index-points, some or all open apertures 81 will not be cancelled by black marks when in the analysing position, and consequently an amount of light sufficient to trip the photocell will penetrate into the interior of drum 21. The photocell 80 when tripped actuates a magnet 110 (Figure 4) to close the sorting flap 69, as shown in dotted lines in Figure 1, which guides the record 13 into another bin 71 reserved for "wrong" records.

It will be evident that in order to ensure proper selection of records, the index points on each record must be accurately aligned with the analysing apertures 81. However, as above mentioned, even a carefully adjusted paper feed may occasionally fail to move a record exactly into analysing position; further, some records may be inaccurately printed, or may be damaged, or they may stick together. In each case, such incorrectly printed, fed, or damaged records (referred to commonly as "incorrect records") will not be properly analysed by the machine.

According to the present invention a control device is arranged to prevent all such incorrect records from being analysed by the machine, and to separate them from "correct" records.

In the embodiment of the invention shown in the drawings, the control device is actuated by a control mark 200, Figure 5, printed on each record 13 between the leading edge and the index-points 88 in such a way that the control mark 200 cuts across the beam of light before the first row of index-points are aligned with the first row of analysing apertures 81. As shown in Figure 2, a lamp 201, additional to the lamp 72, is mounted, underneath the drum 21, in a socket 202, secured to a bracket 203 fixed to casing 78 of the analysing lamp 72, so that both lamps 201, 72 are substantially in the same plane. Secured to the bracket 203 is a casing 204 enclosing the lamp 201 and provided with an aperture 205 facing the drum 21, the feed roller 21 of the machine being recessed as at 206 to allow free passage of light to an aperture 207 in the wall of the drum. For the purpose of illustration this control aperture 207 is shown in Figure 2 in the same plane as a row of analysing apertures 81, but in practice it is actually positioned in front of the latter, viz: in a position in which it will be able to co-operate with the control mark 200 on records 13 before the analysing apertures 81 come into operation. The size of control aperture 207 corresponds to the open area within the control mark 200, so that the beam of light, after passing through aperture 205 and the said open area, illuminates an area on drum 21 approximately equal to the control aperture 207. Thus, assuming the control mark is accurately centred relatively to the aperture 207, a beam of light having a cross-section equal to the area of the control mark will pass through the aperture 207. As shown in Figure 2 slotted mask 78' (similar to mask 78 of the above mentioned prior specification) is preferably provided close to drum 21 in order to prevent stray light impinging on the drum.

A photocell 208 in casing 212 open at the bottom is arranged in the interior of drum 21 in line with the beam of light generated by control lamp 201; it is mounted in a socket 209 fixed to a bracket 210 secured to stationary shaft 48 of drum 21; wires 211 connect the control cell 208 to the amplifier device 88 (Figure 1). The impulses of control cell 208, after being amplified, are conveyed to an electromagnet 213 (Figure 4) through wires 214. Magnet 213 is mounted in a

5 bracket 215 fixed to frame plate 2 by screws 216, a set screw 217 securing the magnet in position. An armature 218 pivoted as at 219 in frame 2, and biased by a spring 220, is arranged to co-operate with magnet 213. Armature 218 serves as a latch coating with a stud 221 on a bail 222, fixed to a shaft 223 journalled in frame plates 1, 2, a spring 224 tending to swing bail 222 clockwise as viewed in Figure 4. Shaft 223 carries a deflector flap 225 formed of three like members fixedly mounted on the shaft in a slot 226 (Figures 3 and 1a) formed in paper guides 67, 68.

10 The armature 218 is normally locked in the position shown in Figure 4 by means to be described hereafter, and it is momentarily released from the locking means when the control mark 200 on a record 13 is aligned with the control aperture 207. If the record or like sheet has been accurately fed into the machine the control mark 200 will be properly aligned with the control aperture 207, the full area of the aperture will be exposed to light passing through the blank area within the control mark, and the control cell 208 will be fully illuminated; the amplified impulse of cell 208 will energise the magnet 213, which will hold its armature 218, thus latching stud 221 and bail 222. Thus, the flap 225 will remain in position shown in full lines in Figure 1a, that is, below the channel formed by guides 67, 68, and allow the record 13 to pass either underneath or above the sorting flap 69, which is controlled in accordance with the analysis of the index-points 88 as described in the above-mentioned prior specification. However, if for any reason the record 13 has not been properly fed, control mark 200 will partially or wholly obscure the control aperture 207, control cell 208 will not be sufficiently illuminated to energise magnet 213, and spring 220 will rock the armature 218 clockwise, as viewed in Figure 4, on to a stop 227, thus detaching stud 221 on bail 222, which will be rocked by its spring 224 on to a stop 228. Consequently, shaft 223 will also rock clockwise, thus elevating flap 225 into position shown in dotted lines in Figure 1, so as to intercept the incorrect record 13 and to guide it into a bin 229 reserved for incorrect records. It will be noted that, as the blank area within the control mark 200 is entirely enclosed by the black area, a maladjustment of the record in any direction will partially or wholly obscure the control aperture 207.

15 If a record has been correctly fed, but the index-points 88 have not been accurately printed on the record, it can be assumed that the control mark 200, too, has not been printed in the exact position it should occupy. Consequently, when the record is in the control position, control mark 200 will be somewhat out of alignment with control aperture 207 and obscure the latter; thus, flap 225 will be operated as described, and the record eliminated. It may be pointed out that if the control mark 200 is entirely out of alignment with aperture 207, the cell 208 will operate as if there was a perfect alignment; thus, in the present embodiment the control mark must be sufficiently large to cope with any inaccuracy of paper feed such as is likely to occur in practice. In case of double feed, the two records will obscure the control aperture due to the reduced transparency of two thicknesses of paper as compared with a single thickness, the magnet 213 will not be energised and the control device will operate the flap 225 as described to deflect the two records into the bin 229. Thus, it will be seen

that the control device will be operated whenever there is an incorrect record, and in this manner the incorrect records are eliminated before they reach the sorting flap 69 which, thus, controls the selection of only properly fed and properly printed records.

The control device above described must operate only when control mark 200 on a record is just passing through the controlling beam of light; this is ensured by the locking device above referred to and now to be described. A cam 230 (Figure 4) having a recess 231 is rigidly mounted on drum 21 so as to rotate therewith. Cam 230 co-operates with a roller 232 journalled in a lever 233 pivoted as at 234 and biased towards the cam by a spring 235. The opposite end of lever 233 carries a trigger 236 pivoted as at 237 and biased by a spring 238 on to a stop 239. Trigger 236 co-operates with a stud 240 carried on the armature 218, and it will be seen that in the position shown in Figure 4 the armature 218 is locked by the trigger 236 abutting against stop 239. Cam 230 is so set relatively to drum 21, which of course rotates in synchronism with the paper feed, that its recess 231 is aligned with the roller 232 at the exact moment when control mark 200 on record 13 is, or rather ought to be, aligned with control aperture 207. When roller 232 drops into recess 231, lever 233 swings anti-clockwise, and trigger 236 releases stud 240, so that armature 218 is free to swing out if permitted to do so by magnet 213. Immediately afterwards roller 232 is moved out of recess 231, thus restoring lever 233 and trigger 236, which again locks stud 240 if armature 218 has remained in the latching position. However, if the armature 218 has been moved away from magnet 213, under the action of the spring 228, trigger 236 when being restored just misses the stud 240, and armature 218 will remain in the delatched position until restored by means now to be described, whereby stud 240 strikes trigger 236 and swings it out of the way by stretching its spring 236.

Flap 225 and armature 218 are restored after each operation by means similar to those described in my above mentioned prior specification 2,319,108 for restoring sorting flap 69 and armature 106 of sorting magnet 110. A rod 121 is shifted to the right (as viewed in Figure 4) after each revolution of drum 21 by cam 52 and lever 124. Fixed to rod 121 is a bush 241 having a finger 242 aligned with an extension 243 on armature 218. Slidably mounted on rod 121 is another bush 244 having a finger 245 aligned with bail 222 on shaft 223, a spring 246 normally pushing bush 244 on to a stop 247. When the rod 121 is pushed to the right, finger 245 engages bail 222 and rocks it until it abuts against a stop 248, thus restoring shaft 223 and flap 225, whereupon finger 242 restores armature 218. When rod 121 again moves to the left, flap 225 remains in the lower position shown in dotted lines in Figure 4, bail 222 being latched by armature 218, and the latter being locked by trigger 236.

In many cases machines of the type affected by the present invention have not only to sort records but also to perform further operations, such as counting or totalizing. For instance, the sorting flap 69 of the sorting machine described in my aforesaid prior U. S. A. Patent specification No. 2,319,108 may be arranged to operate a counter for rejected records. It will be evident that should the paper feed miss a record, the flap 69 will be operated in the same manner as in the case

of a "wrong" record, thus giving a wrong total of rejected records.

This will also be the case if a blank sheet (that is a sheet not having a control mark) is fed through the machine, or if a record is so badly fed that the control mark is completely out of alignment with the control aperture 207.

A modified form of control device may be provided according to a modification of the present invention to eliminate this possibility by rendering the analysing device operative only when a single properly printed record is properly aligned with the controlling beam of light. Thus, if there is no record in the control position, or if the record is "incorrect" or in the case of a blank, the analysing device is rendered inoperative.

In this modification, shown in Figures 6, 7, the control cell 208 is arranged to operate a magnet 250 in exactly the same manner as previously described with reference to magnet 213. This magnet 250 is of solenoid type, its core 251 being linked as at 252 to a three-armed rocker 253 pivotally mounted as at 254 in frame plate 2.

A downwardly extending arm of rocker 253 carries a stud 255 against which normally abuts a stud 256 secured to a bail 257 which, similarly to bail 222 of the first modification, is secured to shaft 223 carrying control flap 225, and is biased clockwise by spring 224. An upwardly extending arm of rocker 253 carries a stud 258 which is normally embraced by a bifurcated end 259 of a double-armed lever 260 pivoted as at 261, which is, similarly to lever 233 of the first modification, biased anti-clockwise by spring 235 and carries a roller 232 coaxing with a cam 262. Cam 262, which has two recesses 263, 264, is rigidly mounted on drum 21, similarly to cam 230 of the first modification. Recess 263 is so positioned on cam 262 as to be aligned with roller 232 just when the control mark 200 on a record 13 is aligned with control aperture 207 in drum 21; at this moment, roller 232 drops into recess 263, the bifurcated lever 260 swings anti-clockwise and releases stud 258 of rocker 253, which is then free to be operated by control cell 208 as will be presently described.

A second solenoid magnet 265 is secured to frame plate 2 opposite magnet 250, its core 266 being linked at 252 to rocker 253 similarly to core 251 of magnet 250. Wires 267 connect magnet 265 to a permanent source of current indicated as at 268. The magnets 250, 265 are arranged to pull in opposite directions, and are so adjusted that, when control mark 200 is properly aligned with control aperture 207, the resulting full illumination of control cell 208 energises magnet 250 to such an extent that its pull is equal to the permanent pull of magnet 265. Consequently, in this case the rocker 253 will remain stationary, its stud 255 continuing to latch stud 256 on bail 257, so that the control flap 225 will remain in the lower position indicated in dotted lines in Figure 6, and the record will not be intercepted, as heretofore described.

In the case of double feed, or if the control mark 200 is not properly aligned with control aperture 207, the control cell 208 will receive a reduced amount of light, and consequently a reduced current impulse will be transmitted to magnet 250; thus, its pull will be less than that of permanent magnet 265, and consequently rocker 253 will swing out clockwise as viewed in Figure 6, its stud 255 detaching stud 256 on bail 257; the latter will be elevated by its spring 224, thus causing the control flap 225 to move into the ele-

vated or open position indicated in dotted lines in Figure 1, and the record will be intercepted and guided into bin 229. Should it so happen that a portion of a record 13 containing the control mark 200 be torn off, or should the paper feed miss a record, no paper will be interposed between control aperture 207 and lamp 201 when recess 263 in cam 262 causes lever 260 to release rocker 253. Consequently, the control cell 208 will receive a greater amount of light than it would normally receive through a thickness of paper, and the impulse transmitted to magnet 250 will be correspondingly greater and will exceed that of permanent magnet 265. Consequently rocker 253 will swing out anti-clockwise as viewed in Figure 6, thus detaching bail 257 to open control flap 225 as described.

Bail 257 has an extension 269 carrying a lug 270 of insulating material, which is adapted to co-operate with a pair of contacts 271. The analysing magnet 110 is normally energised and is arranged to be deenergised by the analysing cell 80 to operate the sorting flap 68. The magnet 110 has two windings, namely, the usual or primary winding connected by wires 118 to amplifier device 68 and controlled by the analysing cell 80 in such a way that the circuit is broken by impulses from the cell, and a secondary winding connected by wires 272 to a permanent source of current indicated as at 273. The secondary winding 272 is normally ineffective, as the contacts 271 are normally open, thus cutting off the supply of current 273. However, during every operation of bail 257 and control flap 225, the lug 270 closes contacts 271, thus establishing a circuit through secondary winding 272; consequently, the analysing magnet 110 remains energised regardless of any operation of the primary winding 118 by the analysing cell 80, so that this energising of the secondary winding 272 amounts to cutting-out the analysing device whenever an incorrect record is fed through the machine. If the analysing magnet 110 were arranged to be energised (and not, as in the present case, to be deenergised) by the analysing cell 80 in order to operate the analysing device, the lug 270 would be arranged to break the circuit of the analysing magnet 110, thus rendering it ineffective with regard to incorrect records; in this case, secondary winding 272 and permanent source of current 273 could be dispensed with.

Movement of rocker 253 can be adjusted by set screws 274 in a bracket 275 secured to frame plate 2. After each working cycle, rocker 253 and bail 257 are restored by members 242, 245 as already described with reference to armature 218 and bail 222, respectively, of the previously described modification (if the rocker 253 has been previously swung clockwise as viewed in Figure 6) thus restoring the control flap 225. If the rocker 253 has been swung anticlockwise, it is restored by a finger 242¹ secured to the rod 121, its upper end being in line with the lower end of core 251 of the magnet 250. The top part of finger 242¹ is sloped to form a cam surface which, when the finger is shifted to the right as viewed in Figure 6, pushes the core 251 upwards and so restores the rocker 253 into the normal position. Prior to this restoring operation, however, the bifurcated end 258 of lever 260 must be moved out of the way of stud 258 on rocker 253. For this purpose, the second recess 264 is arranged in the cam 262 in such a position as to be aligned with roller 232 on lever 260 just prior to the restor-

ing operation of rod 121, thus causing lever 260 to clear rocker 253 as already described.

As already mentioned, a control mark of the kind shown in Figure 5 will not operate the control mechanism if it is completely out of alignment with control aperture 207; this will also be the case if a blank sheet without any control mark is fed into the machine. In order to meet this possibility, however remote, control marks of the kind shown in Figures 8 and 9 may be used. These marks differ from the mark shown in Figure 5, in that a small opaque area is inserted in the blank or transparent area within the control mark, this additional opaque area being of any suitable shape. For use with control marks of this kind, the magnets 250, 265 are so adjusted that their pulls are equal when the control cell 208 receives light passing through the remaining transparent area within the control mark. It will be seen that if, at the time of control operation, a blank portion of a record be exposed to the controlling beam, an amount of light greater than the standard amount will reach the control cell; consequently, the pull of magnet 250 will exceed that of permanent magnet 265, thus operating the control flap 225 as described. Otherwise, the control operation is exactly the same as in the case of the control mark illustrated in Figure 5.

The control device according to the present invention has been described with reference to light energy, but it will be evident that any other suitable form of radiant energy (for instance, infra-red rays) can be used, providing it is capable of being influenced by semi-transparent paper sheets. If another form of radiant energy were to be used, the light source 201, the photocell 208, and the control marks 200 would be replaced by devices generating, sensitive to, and impervious to, respectively, the particular form of radiant energy used.

This invention is not limited in its application to the assorting machine described in my above mentioned prior patent; it may be usefully applied to sorting, segregating, selecting, accounting, tabulating, interpolating, counting, typesetting, repetition printing and other machines using printed or otherwise marked sheets or records, whenever these machines require accurate feeding for proper operation.

What I claim is:

1. In a machine having a feeding device for paper and like sheets, means for segregating "incorrect" sheets from "correct" sheets, comprising 55 a photoelectrical analysing device adapted to co-operate with a control mark on the sheets fed into the machine in order to produce standard impulses in the case of accurate feeding of the sheets, and non-standard impulses in the case of inaccurate feeding of the sheets, an electromagnetic device operatively associated with said analysing device and adapted to be actuated only by said non-standard impulses, mechanical holding means for rendering the electromagnetic device inoperative until such time as the control mark on a sheet should, in the case of accurate feeding, be in alignment with the analysing device, means for thereupon momentarily releasing said holding means, said holding means and said releasing means comprising a cam rotating synchronously with said paper feeding device, means for operatively associating said cam with said magnetic device, and a deflector flap operated by said magnetic device when the latter is actuated to deflect the sheets responsible for produc-

ing the non-standard impulses so that they do not cooperate further with the machine.

2. In a machine according to claim 1 a locking member adapted to be displaced by the non-standard impulses received by the electromagnetic device to hold the machine inoperative for the remaining of the working cycle of the machine.

3. A machine according to claim 1 wherein the electromagnetic device comprises a latching member adapted normally to latch the flap in an inoperative position, said latching member constituting an armature for the electromagnetic device which normally maintains the latching member in latching position, and further comprising a spring acting on said latching member and tending to move it into the unlatched position, and means for restoring the latching member, when it has been delatched, into the latching position before each fresh cycle of operation.

4. A machine according to claim 1 wherein the electromagnetic device comprises one magnet exerting a substantially constant force, a second magnet controlled by impulses received from the sensitive device and arranged to exert a force opposite in direction to that exerted by the first magnet, and an element movable from a normal position in either direction under the resultant action of said magnets, said element normally latching the deflector flap in an inoperative position and unlatching said deflector flap for operation when moved in either direction from the normal position.

5. A machine according to claim 1 wherein the electromagnetic device comprises one magnet exerting a substantially constant force, a second magnet controlled by impulses received from the sensitive device and arranged to exert a force opposite in direction to that exerted by the first magnet, a latching device normally latching said deflector flap in an inoperative position but movable under the action of said magnets to delatch said deflector flap, and means for restoring said latching device, when it has been delatched, into the latching position before each fresh cycle of operation.

6. A machine according to claim 1 further comprising a drum the wall of which has an aperture and which is adapted to move between the source of radiant energy and the device sensitive thereto, and means for rotating said drum to bring said aperture into alignment with the source of radiant energy and the device sensitive thereto simultaneously with the control mark on a correct sheet, whereby the correct alignment or otherwise of said control mark relatively to said aperture controls the operation of the deflector flap.

7. A machine according to claim 1 further comprising a photoelectric analysing device for analysing record cards and like sheets.

8. A machine according to claim 1 further comprising a photoelectric analysing device for analysing record cards and like sheets, an electric switch controlling the operation of said photoelectric analysing device, and means for operating said switch to render said analysing device inoperative when the deflector flap is moved to deflect an incorrect record.

9. In a control device for use in machines through which paper and like relatively transparent sheets are passed, mechanism designed to prevent normal operation of the machine by "incorrect" sheets, a source of radiant energy, a device sensitive to said radiant energy, an opaque mask operatively disposed in the path of the radiant energy between said source of radiant energy and said sensitive device, said mask having a transparent area arranged to co-operate in a control position in the machine with a control mark comprising a transparent area enclosed in an opaque area provided in a predetermined position on a sheet passing through the machine, whereby the maximum amounts of radiant energy which can pass through the said two transparent areas are substantially equal in the case of "correct" records and unequal in the case of "incorrect" records, and means operated by said sensitive device, when the amounts of radiant energy passing through the two transparent areas are unequal, to operate said mechanism.

10. In a control device for use in machines through which paper and like sheets are passed, mechanism designed to prevent normal operation of the machine by "incorrect" sheets, a source of radiant energy, a device sensitive to said radiant energy, a mask operatively disposed in the path of the radiant energy between said source of radiant energy and said sensitive device, said mask having a transparent area adapted to co-operate in a control position in the machine with a control mark provided in a predetermined position on a sheet passing through the machine, said control mark comprising an outer opaque portion enclosing an inner portion smaller in area than the transparent area in the mask, whereby the maximum amount of radiant energy which can pass through said inner portion is less than that which can pass through the transparent area in said mask, and means, operated by said sensitive device, for operating said mechanism whenever the amount of radiant energy impinging on the said sensitive device differs from said maximum amount.
